UNITED STATES PATENT OFFICE.

ARNOLD NACKE, OF PHILADELPHIA, PENNSYLVANIA.

DESIGN FOR A TABLE.

SPECIFICATION forming part of Design No. 22,539, dated June 13, 1893.

Application filed March 10, 1893. Serial No. 465,433. Term of patent 3½ years.

To all whom it may concern:

Be it known that I, ARNOLD NACKE, of Philadelphia, county of Philadelphia, and State of Pennsylvania, have invented a new 5 and useful Improvement in a Design for Tables, of which the following is a specification.

This invention comprises a design for ornamental tables and consists essentially of a bust of Columbus applied to a panel in the 10 frame of the table and surrounded by an ornamental wreath and outside scroll-work, substantially as hereinafter more fully described.

The design is especially intended to be applied to that class of ornamental parlor tables 15 comprising a frame and legs of metal, and a top of ornamental stone, glass or marble, though it may be applied to other varieties of tables.

The accompanying drawing represents a 20 front view of a table with my design applied thereto.

II designates the rectangular frame of the table and I the curved legs. The frame is of sufficient depth, vertically, to form side panels 25 of sufficient width to receive the bust and ornamentation which together constitute my design.

A designates a bust of Columbus applied

to the center of the panel, and B a surrounding wreath forming an ornamental border 30 around the bust. Beyond, or outside of the wreath the panel is ornamented with scroll-work D, which fills the panel and extends from the wreath to the ends and down upon the legs of the table as shown.

The essential characteristics of the design 35 are a bust of Columbus applied centrally to a panel in the frame of a table, a surrounding and inclosing wreath forming an ornamental border around the bust, and outside 40 scroll work extending from the wreath to the ends of the panel and upon the upper portions of the legs of the table.

Having thus described my invention, what I claim is—

The design for a table as hereinbefore described and illustrated in the accompanying drawings.

In testimony whereof I hereunto set my hand, this 17th day of February, 1893, in the 50 presence of two attesting witnesses.

ARNOLD NACKE.

Witnesses:

ROBERT OSBORNE, Jr.,
ALBERT BRINKMANN.
